UNITED STATES PATENT OFFICE.

EDWARD J. DACEY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

JACQUARD MECHANISM FOR LOOMS.

Application filed September 2, 1924. Serial No. 735,258.

This invention relates to a jacquard mechanism for looms and is especially designed for use in weaving double fabrics. Such a fabric is shown in my co-pending application Serial No. 678,778, filed December 5, 1923, Patent Number 1,525,496. In weaving such fabrics, it is necessary to separate the warp threads to form two different sheds and it is also necessary to pass certain pile 10 warps from one fabric to the other to form pile.

It is the general object of my invention to provide a jacquard mechanism by which such double fabrics may be conveniently 15 woven and by which other useful results may be attained.

My invention further relates to arrangements and combinations of parts which will be hereinafter described and more particularly pointed out in the appended claims.

A preferred form of the invention is shown in the drawings in which

Fig. 1 is an end elevation of my improved jacquard mechanism;

Fig. 2 is a side elevation thereof;

Fig. 3 is a sectional end elevation, taken along the line 3—3 in Fig. 2;

Figs. 4, 5 and 6 are diagrammatic end elevations, showing the parts in different positions;

Figs. 7, 8 and 9 are detail views illustrating corresponding warp positions; and

Fig. 10 is a sectional view of a weave which may be produced by my improved mechanism.

Referring to the drawings, my improved jacquard mechanism comprises end frames 10 and 11 (Fig. 2) mounted on a base or support 12 and held in definite spaced relation by cross rods 13 and cross frame members 14. A plurality of upright rods 15 (Fig. 1) are fixed in the end frames 10 and 11 and form guides for the vertically moving lifter frames 16, 17, 18 and 19. A plurality of lifter bars 20, 21, 22 and 23 are carried by the lifter frames 16, 17, 18 and 19 respectively, these bars extending across the jacquard mechanism as clearly shown in Fig. 2. The lifter frames 16, 17, 18 and 19 are actuated by connector rods 24, 25, 26 and 27 at each end of the frames, said rods being connected at their lower ends to an actuating lever or rocker 28 which may

be moved intermittently through an arm 29 and a link 30 by any suitable actuating mechanism (not shown).

The jacquard mechanism is provided with the usual lifter wires 31 each having a hook 32 (Fig. 3) at its upper end and also having its lower end formed in a reverse bend 33 and provided with a laterally projecting hook 34. The wires are controlled by the usual jacquard cylinder 35 (Fig. 1) which carries the pattern cards and which is reciprocated on the rods 36 by suitable driving mechanism (not shown) operating through a link 37, bell crank 38 and link 39. The pattern cylinder and its driving mechanism is of the usual type and in itself forms no part of my present invention.

It will be noted that the connecting rods 25 and 26 are attached to the rocking levers 28 at points substantially twice as far from the axis as the connecting rods 24 and 27. Consequently the vertical movement of the lifter frames 17 and 18 and of the lifter bars 21 and 22 is substantially twice that of the frames 16 and 19 and of the lifter bars 20 and 23. This proportionate movement is required to give the necessary travel of the selected pile warps from the upper fabric to the lower fabric or from the lower fabric to the upper fabric to form the connecting pile.

The type of double weave shown in my co-pending application is disclosed in Fig. 10, in which a full set of color or pile warps is shown in both the upper and lower fabrics, so that any color may be called at any time from either fabric portion. In the weaving of this type of fabric, the successive steps shown in Figs. 7, 8 and 9 correspond to the successive positions of the jacquard mechanism shown in Figs. 4, 5 and 6.

In Figs. 4 and 7 the machine parts and warp threads are in the position which they assume at the time when the jacquard pattern selects the warp threads to be raised or lowered. In this position, all of the color warps 40 in the upper fabric are raised, being controlled by the lifter frame 18, and all of the lower color warps 41 are depressed, under the control of the lifter frame 19. The hooks 32 at the upper ends of all of the lifter wires are then free from the lifter bars on the frames 16 and 17 and may be

selectively positioned by the jacquard pattern.

The hooks 32 of the wires 31 for the upper color warps 40 will be moved off of the upper lifter bars for such warps as are designed to move downward and form the pile at the next operation of the loom. At the same time, the hooks 32 of the wires 31 for the lower warps 41 which are to be raised 10 to form the pile will be located to engage the lifter bars on the frame 17, while the remaining wires are free from such engagement and are supported on the short travel frame 19.

15 As the jacquard then moves to the mid-position shown in Fig. 5, the warp threads commence their travel in opposite directions. The selected pile warps move to the center of the fabric and the remaining pile warps 20 have a movement equal to about one half the travel of the selected warps. When the movement of the jacquard is completed, as indicated in Fig. 6, the pile warps assume the positions indicated in Fig. 9. In this 25 position, the warps selected to form the pile have been raised or lowered for the extreme travel of the frames 17 and 18, while the remaining warps have received only one half of the travel and form the center of the double shed.

With this explanation, it will be seen that my improved jacquard mechanism provides means by which any color or pile warp may be given either a short or a long travel 35 according to whether it is under the control of the short travel lifter frames 16 and 19 or the long travel frames 17 and 18.

The movements of the binder warps 42 have been omitted from this description, as 40 these warps are moved in the usual way by separate harnesses and are not controlled by the jacquard mechanism. The weave shown in the drawings is illustrative only and it will be understood that my improved 45 jacquard mechanism is equally well adapted to the formation of many other types of weave.

Having thus described my invention and the advantages thereof, I do not wish to be limited to the details herein disclosed otherwise than as set forth in the claims, but what I claim is:—

1. In a jacquard mechanism for a double fabric loom having duplicate sets of pile forming yarns, one set for each fabric, a pair of movable members for each set of yarns, means to move one pair of members in a direction opposite to that in which the other pair of members moves, each pair lifting 55 all the yarns corresponding thereto on each movement of the jacquard whereby the weight of the yarns carried by the members moving in one direction is balanced by the weight of the yarns carried by the members 60 moving in the opposite direction.

2. In a jacquard mechanism for a double fabric loom having duplicate sets of pile forming yarns, one set for each fabric, a rocking member, a pair of yarn controlling members for one set connected to one side 70 of the rocking member, another pair of yarn controlling members for the other set connected to the other side of the rocking member whereby said pairs will move in opposite directions.

3. In a jacquard mechanism for a double fabric loom having duplicate sets of pile forming yarns, one set for each fabric, a rocking member, a pair of yarn controlling members for one set connected to one side 80 of the rocking member, another pair of yarn controlling members for the other set connected to the other side of the rocking member whereby said pairs will move in opposite directions, the members of each pair supporting the weight of the yarns of the set corresponding thereto so that the weight supported on each side of the rocking member is substantially the same and in balance.

4. In a jacquard mechanism for double 90 fabric looms having duplicate sets of yarns, one set for each fabric, two pairs of movable members, one pair for each set, one of the members of each pair having a greater movement than the other member to move a relatively small part of the yarns of the set corresponding thereto to pile forming position, and means to support and move said pairs simultaneously in opposite directions, the member of each pair having the lesser movement supporting the greater amount of yarn, whereby the weights of yarn supported by the members are substantially the same and in balance.

5. In a jacquard mechanism for a double 105 fabric loom having duplicate sets of yarns, one set for each fabric, a lever rocking about a pivot, two pairs of movable members, one pair for each set of yarns, one pair being attached to the lever on one side of the pivot 110 and the other member being attached to the lever on the other side of the pivot, one member of each pair receiving a relatively larger movement and adapted to lift a comparatively small number of pile forming yarns, the other member of each pair lifting the remainder of the pile forming yarns, the members for lifting the lesser number of yarns being attached to the lever on opposite sides from and substantially equally distanced from the pivot of the lever, and the members for lifting the larger number of yarns being connected to the lever intermediate the other members and the pivot of the member at points substantially equal from the pivot of the lever.

6. A jacquard mechanism for looms having two duplicate sets of pile forming yarns, one set for each fabric, said mechanism comprising a pair of movable lifting members 130

for each set of yarns, one member of each pair having a greater movement than the other member of said pair, and means to give both members of one pair an operative upward yarn lifting movement and to simultaneously give both members of the other pair an idle downward movement, whereby

pile yarn from one set of yarns only may be raised at any given time to pile forming position.

In testimony whereof I have hereunto affixed my signature.

EDWARD J. DACEY.
